UNITED STATES PATENT OFFICE.

ROBERT LEE NOURSE, OF HAILEY, IDAHO.

OVEN-THERMOMETER.

SPECIFICATION forming part of Letters Patent No. 645,371, dated March 13, 1900.

Application filed October 10, 1899. Serial No. 733,207. (No model.)

To all whom it may concern:

Be it known that I, ROBERT LEE NOURSE, a citizen of the United States, residing at Hailey, in the county of Blaine and State of Idaho, have invented certain new and useful Improvements in Oven-Thermometers; and I do declare the following to be a full, clear, and exact description of the invention, such as will enable others skilled in the art to which it appertains to make and use the same.

My invention relates to improvements in oven-thermometers for cooking purposes; and the object is to simplify and improve the construction and increase the efficiency and utility of the device.

To these ends the invention consists in the construction, combination, and arrangement of the several elements of the device, as will be hereinafter more fully described, and particularly pointed out in the claim.

In the accompanying drawings the same reference characters indicate the same parts of the device.

Figure 1 is a front elevation of my improved oven-thermometer as it appears on the oven-door. Fig. 2 is a vertical section through the mercury-column. Fig. 3 is a horizontal section on the line 3 3 of Fig. 2.

A denotes the oven-door, which is provided with an orifice *a* for the insertion of the thermometer-tube and with bolt-holes *b* and *b'* for the reception of the bolts *B* and *B'*.

2 denotes the sheet-metal case, which is provided with the bolt-holes *2'* *2''*, the orifice *2³*, and the longitudinal parallel flanges 3 3, which form the protecting-walls of the groove 4, in which the graduated stem of the thermometer is mounted.

5 denotes a cap or hood which encompasses

the end of the thermometer-tube and is itself 40 held in place by the bolt *B*.

6 denotes a curved guard-plate which encompasses the thermometer-bulb to protect it against injury, and this plate or shield is fixed to the inside of the oven-door by the 45 bolt *B'*.

The body of the case 2 on either side of the flanges 3 3 is provided with an indicating-scale, as shown in Fig. 1, to indicate the proper temperature of the oven at which the 50 various articles of food should be cooked.

The accompanying drawings show my invention in the best form now known to me; but many changes in the details might be made within the skill of a good mechanic 55 without departing from the spirit of my invention as set forth in the claim at the end of this specification.

Having thus fully described my invention, what I claim as new and useful, and desire to 60 secure by Letters Patent of the United States, is—

In combination with the oven-door provided with the orifice, *a*, and bolt-holes, *b* and *b'*, the casing formed with the bolt-holes, *2'* 65 *2²* and *2³*, and the parallel flanges, 3 3, the thermometer-tube having its bulb arranged on one side of the door and its graduated stem on the other, the cap, 5, the curved guard-plate, 6, and the bolts, *B* and *B'*, substantially as shown and described.

In testimony whereof I have hereunto set my hand in presence of two subscribing witnesses.

ROBERT LEE NOURSE.
